UNITED STATES PATENT OFFICE.

LOUIS SANDERS, OF BROOKLYN, ASSIGNOR TO ELIZA SANDERS, OF NEW YORK, N. Y.

WAIST-BELT.

SPECIFICATION forming part of Reissued Letters Patent No. 10,612, dated June 16, 1885.

Original No. 312,168, dated February 10, 1885. Application for reissue filed March 24, 1885.

To all whom it may concern:

Be it known that I, LOUIS SANDERS, of Brooklyn, in the county of Kings and State of New York, have invented certain new and 5 useful Improvements in Waist-Belts, of which the following is a specification.

This invention has reference to an improved lady's waist-belt which can be readily adjusted to any size of waist, and which presents 10 a neat and finished appearance.

In the accompanying drawings, Figure 1 represents a perspective view of my improved lady's waist-belt. Fig. 2 is a detail side view of the inner and outer ends of the same, and 15 Fig. 3 is a detail horizontal section of the buckle on line x x , Fig. 1.

Similar letters of reference indicate corresponding parts.

A in the drawings represents a lady's waist-belt, which is provided at the inner end with 20 a series of holes, a , re-enforced by eyelets, and with an adjustable buckle, B, that is slipped by its center bar over the belt and provided at one side with a backwardly-projecting hook-shaped tongue, b , that is inserted into one of 25 the holes a . The buckle B is further provided at its opposite side with forward-projecting headed studs d d , which take into slots d' d' of the opposite or front end of the belt A.

30 The slots d' d' are re-enforced by a metal plate or plates, d'' , the slots being wide enough at one end for the passage of the heads of the

studs d d and narrower at the other end for the shanks of the same. A sliding loop, e , is placed over the outer end of the belt after the 35 same has been closed.

Having thus described my invention, I claim as new and desire to secure by Letters Patent—

1. A belt having a series of eyelets near one end, in combination with an adjustable sliding 40 plate provided with an inwardly-turned hook for engaging said eyelets, a loop on the inside of the plate for holding the plate to the belt-strap, and a headed projection on the outside of the plate for engaging the other end of the 45 belt, substantially as described.

2. The combination of a belt, provided at its outer end with a fixed slotted metallic plate and at its inner end with a series of holes, and an adjustable buckle, consisting of a plate 50 provided on its under side with a loop, through which the belt passes, at its rear edge with an inwardly-projecting hook, which grasps said belt through one of said holes, and on its face or front side with outwardly-projecting headed 55 studs, which interlock with said fixed slotted plate, substantially as set forth.

In testimony that I claim the foregoing as my invention I have signed my name in presence of two subscribing witnesses.

LOUIS SANDERS.

Witnesses:

PAUL GOEPEL,
SIDNEY MANN.
